H. S. FRANK,
CENTRIFUGAL CASTING MACHINE,
APPLICATION FILED DEC. 13, 1917.

1,283,139.

Patented Oct. 29, 1918.

UNITED STATES PATENT OFFICE.

HARRY S. FRANK, OF ST. LOUIS, MISSOURI, ASSIGNOR TO INLAND MACHINE WORKS,
OF ST. LOUIS, MISSOURI, A CORPORATION OF MISSOURI.

CENTRIFUGAL CASTING-MACHINE.

1,283,139.

Specification of Letters Patent. Patented Oct. 29, 1918.

Application filed December 13, 1917. Serial No. 206,873.

To all whom it may concern:

Be it known that I, HARRY S. FRANK, a citizen of the United States, residing at the city of St. Louis and State of Missouri, have 5 invented a new and useful Centrifugal Casting-Machine, of which the following is a specification.

This invention relates to centrifugal casting machines.

10 An object of the invention is to provide an improved centrifugal casting machine comprising a rotatable cylinder adapted to receive the molten metal while being driven at a high rate of speed, in combination with a 15 delivery or supply trough movable into the cylinder while the latter is in operation and adapted to be turned or tilted to position to pour the molten metal into the rotatable cylinder to make even distribution of the metal 20 therein from end to end of the cylinder, so that very slight flow of the metal is required in order to produce the casting of approximately uniform thickness and density throughout.

25 Another object of the invention is to provide a device constructed and operating in the manner mentioned in which the cylinder is provided with internal channels or 30 grooves adapted to receive the molten metal and to form a plurality of cast rings at each operation.

A further object of the invention is to provide a centrifugal casting machine for the manufacture of ring blanks adapted for use, 35 when finished, as piston rings and comprising a rotatable cylinder having a plurality of internal channels or grooves adapted to receive the molten metal while the cylinder is in rotation and provided with connecting 40 gates or passages through which the molten metal may flow to effect even distribution thereof throughout, so that all of the rings will be of uniform size and density, and when cut or split and finished will constitute 45 piston rings adapted to be used upon engine pistons.

Other objects will appear from the following description, reference being made to the drawing, in which I have illustrated the es-

sential features of the invention, and in 50 which—

Figure 1 is a plan view of the machine.

Fig. 2 is a longitudinal sectional view of the machine constructed for casting a cylinder having its wall in uniform thickness and 55 provided with a flange at one end.

Fig. 3 is a sectional view of a similar machine in which the cylinder is formed with a series of internal grooves or channels for casting rings.

Fig. 4 is a cross sectional view on the line 4—4 of Fig. 3.

Fig. 5 is an end elevation of the casting machine, the supply trough being in section along the line 5—5 of Fig. 2.

Fig. 6 is a view, part in elevation and part in section of the casting produced by the machine illustrated in Fig. 3, in which the casting is composed of a series of rings integrally connected by the metal entering the 70 passages or gates between the channels or grooves in the cylinder.

The machine illustrated in Figs. 1 and 2 is supported upon the base 1. In this form of the invention there are two frames or stands 75 2 secured to the base and provided with bearings in which the rotatable cylinder is supported. The bearings are surrounded preferably by passages 3 through which cool currents of water or air may be circulated 80 from the supply pipes 4.

The cylinder is composed of two separate sections having their edges matching and abutting closely together in order to form perfect and unbroken joints so that there 85 will be no imperfection in or upon the casting produced by operation of the machine. The section 5, for convenience, may be termed the lower section, and the section 6 may be termed the upper section. As apparent by reference to the drawings, when these two sections are placed together they form a perfect cylinder. The two sections are of equal length and on their ends have annular flanges 7 which encircle the shoulders 8 on the journal supporting members. Each journal supporting member is composed of a tubular axial portion 9 and a cir-

5 circumferential flange 10, the shoulders 8 being formed on the flanges 10. The lower section 5 of the cylinder is rigidly secured in connection with the journal supporting members by screw bolts 11 passing through the flanges 10 and engaging the section 5. The section 6 is removably supported between the journal supporting members and is retained in connection with the section 5 by a clamp 10 specially provided for that purpose.

The clamp is composed of two arcuate members, one of which is permanently attached to the section 5 and pivotally supports the other member. As illustrated, the member 12 of the clamp is held in connection with the lower section 5 by screw bolts 13 passing through the member 12 and entering extended portions 14 on said section 5. The upper member 15 of the clamp is connected to the lower member at one end by a pivot 16 and is arranged to extend over the upper section 6 of the cylinder. The opposite end of the clamp member 15 is formed with a bifurcation 17 adapted to receive the reduced portion 18 on the end of the member 12. The bifurcation 17 and the reduced portion 18 are formed with registering holes adapted to receive the locking pin 19 of the clamp so that when the cylinder is closed and 80 the clamp is placed about the same, the locking pin 19 may be driven in and the parts held rigidly together so that they will not work loose during the rapid operation of the machine. For pressing the two sections 35 of the cylinder together, the member 15 of the clamp supports a pressure device composed of a screw 20 and a handle 21 by which the screw may be operated to press against a boss formed on the section 6 of the cylinder 40 in the manner shown in Figs. 2 and 3.

The journal members 9 are mounted in bushings 22 located in the bearings in the supporting frames and one of the journal members supports a pulley 23 adapted to be 45 driven by a belt 24, or other appropriate driving connection.

The temperature of the cylinder may be reduced by streams of cold water delivered thereto from supply pipes 25 having delivery 50 faucets 26 arranged to discharge the water upon the cylinder as it is in rotation, and provided with valves 27 whereby the flow of the water may be controlled.

The cylinder formed by the matching sections 5 and 6 has an internal diameter in excess of the openings at the ends of the cylinder, there being internal flanges 28 which confine the molten metal within the cylinder. In the form illustrated in Fig. 2, the interior 60 of the cylinder thus constructed is provided with an internal channel or groove 29 at one end so that the cylindrical casting produced will be provided with a circumferential flange at that end.

The molten metal is supplied to the cylinder by a delivery or supply device comprising a trough 30 mounted on a movable support 31. The support 31 is mounted in a frame or bearing 32 in alinement with the cylinder so that by moving the support 31 toward the cylinder the trough 30 will be moved into the cylinder in position to be turned or tilted to discharge the molten metal. Movement of the support 31 is limited by an abutment 33 secured thereto and arranged to contact with the frame at the time the trough 30 is in position to discharge the molten metal throughout the length of the cylinder. Thus no attention is required for the accurate movement of the trough into 80 the cylinder, since the trough will be stopped in accurate position at each movement. A handle 34 secured to the abutment 33 constitutes means for manipulating the support 31 and thereby the trough 30 into and out 85 of the cylinder. A weight 35 also supported by the abutment 33 constitutes an actuator for automatically turning the trough 30 to its proper position for receiving the molten metal after each operation, and said actuator 90 is also effective to prevent undesired tilting or turning of the trough.

The form of the invention illustrated in Figs. 3 and 4 is the same as that described above, with the exception of the internal construction of the cylinder. In the embodiment illustrated in Figs. 3 and 4 the interior of the cylinder is formed with a plurality of grooves or channels 36 so that when the molten metal is poured into the rotating cylinder it will enter said grooves or channels and form a series of rings. This embodiment of the invention is specially adapted for use in the manufacture of ring blanks from which piston rings are made. After 105 the ring blanks have been formed in the machine it is only necessary to cut or split them and face them off to proper finish and they are then ready for use.

In order to facilitate or assure the even 110 and uniform distribution of the metal into and through all of the grooves or channels 36 there may be provided a series of notches or passages 37 connecting the various grooves to permit flow of the metal throughout. The molten metal will thus enter all 115 of the grooves or channels and also the passages 37 so that when the metal hardens into a casting the rings are integrally united by that portion of the metal which has entered 120 the gates or passages 37. These small connections may be readily cut and the rings faced off to proper size.

It is apparent that there may be various other modifications in the construction of 125 the machine without departure from any of the principles herein disclosed. I do not restrict myself to specific features of con-

struction and arrangement, but what I claim and desire to secure by Letters Patent, is:—

1. In a centrifugal casting machine, a rotatable mold composed of two matching abutting sections, a clamping member pivotally supported by one of said sections for holding the two sections together, means for holding the clamping member in clamping position, said means being releasable to permit release of the clamping member and separation of said sections, a pressure device carried by said clamping member for pressing one of the mold sections against the other, bearings supporting the mold, and a supply trough movable into and out of the mold.

2. In a centrifugal casting machine, a mold comprising two separable sections, journal members permanently attached to one of said sections, bearings in which said journal members are mounted, a clamping member carried by the mold section which is in permanent connection with the journal members, another clamping member pivoted thereto and adjustable in position to clamp the other mold section in operative position, means for securing said clamping members together, means for rotating the mold, and means for delivering the molten metal into the mold.

3. In a centrifugal casting machine, a rotatable mold composed of two matching abutting sections, journal members in permanent connection with one of said sections and the other section being separable therefrom, a clamp member pivotally supported by the mold section which is in permanent connection with the journal members, means for securing the clamp member in position to retain the separable mold section in position, and an auxiliary clamp coöperating with said clamp member for pressing the separable mold section into contact with the other mold section.

4. In a centrifugal casting machine, a rotatable mold comprising a mold section revolvably supported, a clamp member carried thereby, a separate mold section adapted to coöperate with the other one to form a complete mold, means for fastening the clamp member in adjustment to retain the separate mold section in position in connection with the other one, an additional device coöperating with the clamp member for pressing the separate mold section into proper adjustment in connection with the other one, and means for supplying molten metal into the mold formed by said sections.

5. A centrifugal casting machine, comprising bearings, journal members supported in said bearings, a mold section, elements connecting said journal members and said mold section, a separate mold section movable into and out of connection with said journal members and said first-named mold section,

a clamp member supported by the first-named mold section, and a device coöperating with said clamp member for pressing the separate mold section into position against the first-named section. 70

6. A centrifugal casting machine, comprising a rotatable mold having an opening at one end, a movable support, a trough carried by said support adapted to contain the molten metal, means for actuating said support to move said trough into said mold and for turning the trough to pour the molten metal therefrom, and means separate from said actuating means for turning the trough to its initial position to receive another load of molten metal after the trough has been moved to its starting point by said actuating means.

7. A centrifugal casting machine, comprising a rotatable mold, a trough movable to and from position to deliver molten metal into said mold, a support for said trough, an actuator for moving said trough into the mold and for tilting the trough to pour the molten metal therein into the mold, and a device separate from said actuator for turning the trough to position to receive molten metal after operation by said actuator. 90

8. A centrifugal casting machine, comprising a rotatable mold composed of two separable sections having grooves or channels in their inner surfaces arranged to receive the molten metal and form rings, a clamp member carried by one of said sections for holding the other section in engagement therewith, and a device coöperating with said clamp member for pressing one of said mold sections toward the other. 100

9. A centrifugal casting machine for casting rings, comprising a rotatable mold composed of two separable mold sections whose combined interior is cylindrical, and the interior surface of the mold formed by said two sections having a number of peripheral grooves therein, said grooves extending unbrokenly entirely around the inner periphery of the mold and being arranged to receive molten metal and form separate unbroken rings thereof, means for holding said mold sections together, means for rotating the mold, and means for delivering molten metal into the mold. 110

10. A machine for casting rings by centrifugal action, comprising a mold composed of two separable sections fitted together, said mold having separate peripheral grooves in its inner surface, said grooves extending unbrokenly entirely around the inner periphery of the mold and being adapted to receive the molten metal, passages connecting said grooves, devices for holding said sections together, means for rotating the mold, and means for delivering molten metal into the mold. 120

11. A machine for casting rings by cen- 130

trifugal action, comprising a mold composed of separable sections in cylindrical form, said mold having a plurality of separate grooves in its inner periphery, said grooves extending unbrokenly entirely around the inner periphery of the mold and being adapted to receive the molten metal, passages connecting said grooves whereby the

metal may flow from each groove into another thereof, means for pressing said separable sections together to form the complete cylindrical mold, means for rotating the mold, and means for delivering the molten metal into the mold. 10
